PISTON GRINDING MACHINE

Herbert A. Silven, Worcester, Mass., assignor to
Norton Company, Worcester, Mass., a corpora-
tion of Massachusetts

Application May 3, 1939, Serial No. 271,451

9 Claims. (Cl. 51—101)

The invention relates to grinding machines, and more particularly to an apparatus for grinding a work piece of a non-circular cross-section, such an oval shape on an automotive piston. 5 One object of the invention is to provide a simple and thoroughly practical grinding apparatus for grinding a work piece to a non-circular shape. Another object of the invention is to provide a grinding apparatus for grinding a work 10 piece of non-circular cross section, in which the work piece is oscillated toward and from the grinding wheel by means of a rotatable cam. A further object of the invention is to provide a piston grinding attachment for grinding an oval 15 or elliptical surface on the periphery of a work piece, such as a piston. Another object is to provide a readily interchangeable master cam which is mounted on the end of the headstock spindle adjacent to the grinding wheel. A further object 20 is to provide a work supporting and driving element which is adjustably mounted on the master cam.

A further object of the invention is to provide a piston grinding attachment in which the piston being ground is moved longitudinally from a grinding position to a truing position and vice versa before and after a truing operation. A further object of the invention is to provide such a piston grinding apparatus with an automatically actuated mechanism for shifting the piston support to and from an operative position before and after a grinding wheel truing operation as the piston is moved to and from its loading and grinding position. Other objects will be in part 30 obvious or in part pointed out hereinafter.

The invention accordingly consists in the features of construction, combinations of elements, and arrangements of parts, as will be exemplified in the structure to be hereinafter described, 40 and the scope of the application of which will be indicated in the following claims.

In the accompanying drawings, in which is shown one of various possible embodiments of the mechanical features of the invention,

45 Fig. 1 is a front elevation of the improved piston grinding apparatus;

Fig. 2 is a fragmentary cross sectional view, on an enlarged scale, taken approximately on the line 2—2 of Fig. 1;

50 Fig. 3 is a fragmentary longitudinal sectional view taken approximately on the line 3—3 of Fig. 2;

Fig. 4 is a fragmentary sectional view, on an enlarged scale, taken approximately on the line 55 4—4 of Fig. 2;

Fig. 5 is a fragmentary cross sectional view, on an enlarged scale, taken approximately on the line 5—5 of Fig. 1;

Fig. 6 is a fragmentary front view, on an enlarged scale, of the lever and cam mechanism for 5 moving the rock bar to and from an operative position;

Fig. 7 is a fragmentary cross sectional view taken approximately on the line 7—7 of Fig. 3; 10

Fig. 8 is a fragmentary horizontal sectional view, taken approximately on the line 8—8 of Fig. 6, through the toggle lever mechanism for 15 rocking the rock bar to and from an operative position.

A cylindrical grinding machine has been illustrated in the drawings comprising a base 10 which supports a longitudinally traversable work supporting table 11 on the usual flat way 12 and V-way 13. The work supporting table 11 is arranged to be traversed longitudinally relative to the base 10 to traverse a work piece and position it in operative relation with a rotatable grinding wheel 15. The table 11 is provided with a depending rack bar 16 by which the table may be 20 traversed by a manual or power operated traversing mechanism. For the sake of illustration, a manually operable traverse mechanism has been illustrated which is identical with that shown in the prior U. S. Patent to C. H. Norton, No. 30 1,299,765, dated April 8, 1919, to which reference may be had for details of disclosure not contained herein. A gear 17 meshes with the rack bar 16 and is rotatably supported on a shaft 18. The shaft 18 also supports a gear 19 35 which is either formed integral with or fixedly mounted relative to the gear 17. The gear 19 meshes with a pinion 20 which may be rotated by means of the manually operable hand traverse wheel 21. By rotation of the hand traverse wheel 40 21 in either direction, a traversing movement of the table 11 may be obtained.

The rotatable grinding wheel 15 is supported on a wheel spindle (not shown) which in turn is rotatably journaled in a transversely movable 45 wheel slide 26. The wheel slide 26 is supported on a transversely extending V-way 27 and a flat way 28 formed on the base 10. The grinding wheel 15 and its supporting spindle may be driven by any suitable driving mechanism such as, 50 for example, an electric motor 29 which is mounted on the upper surface of the wheel slide 26. The motor is provided with a rotatable armature shaft 30 which is provided with a driving pulley 31. The pulley 31 is connected by multiple 55

V-belts 32 with a pulley 33 mounted on the outer end of the wheel spindle.

The wheel slide 26 is arranged to be fed transversely toward and from the work supporting table 44 to facilitate feeding of the grinding wheel 15 toward and from the work axis to grind a work piece to the required extent. The feeding mechanism illustrated in the drawings is substantially the same as that shown in the prior 10 United States patent to C. H. Norton No. 762,838 dated June 14, 1904, to which reference may be had for details of disclosure not contained herein. A half nut 35 depending from the wheel slide 26 meshes with or engages a rotatable cross feed 15 screw 36. A forwardly extending portion 37 of the feed screw 36 carries a gear 38 which in turn meshes with a pinion 39. A manually operable feed wheel 40 is either formed integral with or fixedly mounted to the gear 38 so that 20 rotation of the manually operable feed wheel 40 is transmitted through the gear 38, the gear 39, the shaft 37, and feed screw 36 to cause a transverse feeding movement of the half nut 35, the wheel slide 26, and the grinding wheel 15. 25 A pivotally mounted feeding stop 41 is provided which is arranged to engage an adjustably positioned abutment (not shown) carried by a micrometer adjusting mechanism 42 to facilitate fine adjustment of the feeding mechanism so as 30 to compensate for wheel wear. When the feed wheel 40 is rotated in a counterclockwise direction, an infeeding movement of the grinding wheel 15 is obtained, and similarly when the feed wheel 40 is rotated in the reverse direction, a 35 rearward movement of the grinding wheel is obtained.

The table 44 serves as a support for a rotatable work supporting mechanism. A pair of spaced members 45 and 46 are mounted on the upper 40 surface of the swivel table 44. These members 45 and 46 are provided with journal bearings 47 and 48 which serve as a support for the reduced end portions 49 and 50 of a cylindrical bar 51. The bar 51 serves as a rotatable support for a 45 rock bar 52. In order that the rock bar 52 may rock freely relative to the shaft 51, anti-friction bearings 53 and 54 are interposed between the ends of the rock bar 52 and the shaft 51. A headstock 58 and a footstock 59 are formed 50 integral with the rock bar 52. The headstock 58 supports a rotatable headstock spindle 60 in bearings 61 and 62. The left-hand end of the headstock spindle 60 (Fig. 3) is provided with a driving pulley 63 which is connected by a multiple 55 V-belt drive 64 with a multi-grooved pulley 65 which is keyed to the rotateable shaft 66. The shaft 66 is supported by anti-friction bearings 67 and 68 which are in turn supported within an eccentric sleeve 69 which is adjustably mounted 60 in a bearing portion 70 formed in the upper end of a bracket 71 which is fixedly mounted relative to the base member 45. The left-hand end of the shaft 66 is provided with a multi-grooved pulley 72 which is connected by a multiple V-belt drive 65 65 73 with a pulley 74 which is in turn mounted on the end of a motor armature shaft 75. The motor armature shaft 75 is carried by an electric motor 76. The motor 76 is mounted on a base plate 77 which is formed with a dovetailed surface which 70 mates with a correspondingly shaped dovetail surface formed in a base member 78. An adjusting screw 80 is carried by a depending bearing 81 formed on the under side of the base plate 77. The screw 80 is screw threaded into a threaded aperture 82 which is formed integral

with the base member 78. By rotation of the screw 80, the base plate 77 and motor 76 may be moved transversely so as to cause a relative movement between the axis of the motor shaft 75 and the shaft 66 so as to tension the multiple 5 V-belt drive 73.

The sleeve 69 is provided to facilitate tensioning of the multiple V-belt drive 64. The bearing or journal 79 which supports the sleeve 69 is provided with a longitudinally extending slot through 10 its upper wall and a binding screw 85 is provided to clamp the journal securely around the sleeve 69 to hold the sleeve in its adjusted position. To tension the V-belt 64, the binding screw 85 is loosened and the sleeve 69 is then rotated by 15 means of a rod or spanner wrench which is inserted in a hole 86 (Fig. 3) formed in the sleeve 69, sufficiently to properly tension the driving belt 64, after which the binder screw 85 is again tightened to clamp the eccentric sleeve 69 within 20 its supporting bearing member 70.

In order to transmit a rocking motion to the work piece during rotation thereof to generate a non-circular surface on the work piece, such as an oval or elliptical shape on an automobile piston 25 37, a master cam 90 is provided. The master cam 90 is preferably keyed to a frusto-conical nose portion 91 of the spindle 60 (Figs. 3 and 4). A nut or collar 92 which is screw threaded onto a threaded portion at the end of the spindle 60 30 serves to lock the master cam 90 in position on the conical supporting surface 91. This mounting for the master cam 90 is provided to facilitate changing of the master cam when it is desired to change cams for grinding different shapes on 35 successive work pieces.

A master cam roller 95 is rotatably supported on an anti-friction bearing 96 which is in turn supported by a stud 97 which is journaled in a bearing surface 98 formed in the bracket 45 which 40 is fixed relative to the swivel table 44. The stud 97 is held in fixed position relative to the bracket 45 by means of a collar 99 which is screw threaded onto the end of the stud 97. It will be readily apparent from the foregoing disclosure that when 45 the master cam 90 is held in operative engagement with the periphery of the master cam roller 95 during rotation of the headstock spindle 60, a rocking motion will be transmitted to rock the rock bar 52 so as to rock the piston 87 being 50 ground relative to the grinding wheel 15 to grind the desired oval or elliptical shape thereon.

The master cam 90 is normally held in operative engagement with the master cam roller 95 during a grinding operation by means of a yieldable device comprising a spring 100 which surrounds a stud 101. The stud 101 is screw threaded into a plate 102 which is fixed relative to the swivel table 44. The spring 100 is interposed between a threaded collar 103 carried by the stud 101 and 60 a washer 104 which engages a recessed aperture 105 formed within a bracket 106 which is fixedly mounted on the rock bar 52 (Fig. 2). The spring 100 is a compression type spring exerting a pressure to rock the rock bar 52 in a clockwise 65 direction (Fig. 2) to move the master cam 90 into operative engagement with the master cam follower roller 95. As illustrated in Fig. 2, the parts are in a loading position, in which the master cam is separated from the master cam 70 roller by means of a mechanism to be herein-after described during the loading operation. The compression of the spring 100 may be adjusted by turning the stud 101 so that its threaded portion moves up or down relative to its threaded support 75

102, after which the stud 101 is clamped in adjusted position by means of a lock nut 107.

A piston such as employed in the modern automotive engine is a hollow member, one end of which is open and is usually provided with a chamfered or frusto-conical inner surface. To support the headstock end of the piston during the grinding operation, a work holding device is provided comprising a member having a frusto-conical surface 110. An annular ring 111 having the frusto-conical surface 110 formed thereon is fixedly mounted to a face plate member 112 which has an internal cylindrical surface 113 which fits on a cylindrical portion projecting from the master cam 90. The face plate member 112 is held in a fixed position with relation to the master cam 90 by means of screws 114. To change the master cam 90, it is merely necessary to remove the screws 114, thereby removing the face plate member 112 and the work supporting ring 111, after which the threaded collar 92 may be removed and the master cam 90 may be removed from the nosing 91 so that it may be interchanged for a new master cam of the same or different shape for succeeding grinding operations.

In order to drive the work piece 87, a pivotally mounted yoke-shaped driving member 115 is carried by the work supporting member 111. The yoke-shaped member 115 is arranged to pass within the hollow piston 87 and to straddle a pin 116 which is inserted within the wristpin apertures of the piston 87 so that when the headstock spindle 60 is rotated by its driving motor 76, a corresponding rotary movement will be imparted to the piston 87 to be ground. Elongated slots 114a are provided in the face plate member 112, through which the screws 114 pass, to facilitate a rotary adjustment of the plate 112 and the driving member 115 to time the same relative to the master cam.

The other end of the piston 87 is supported by a footstock center 120 which is carried by the footstock 59. The footstock center 120 is supported in a slidably mounted sleeve 121 which is slidably keyed within a sleeve 122. The sleeve 122 is slidably keyed within an aperture 123 formed within the footstock 59. The footstock 59 is provided with a slot 124 extending its entire length and a binder screw 125 is provided by means of which the sleeve 122 may be clamped in adjusted position.

The sleeve 121 supporting the footstock center 120 is moved to and from an operative position by means of a fluid pressure mechanism 55 comprising a cylinder 126 having a piston 127 slidably mounted therein. When fluid is admitted either to a chamber 128 or a cylinder chamber 129, the piston 127 is caused to move either toward the right or toward the left. A yieldable 60 connection is preferably interposed between the piston 127 and the sleeve 121 so that the footstock center 120 may be held in yieldable engagement with the piston 87 during a grinding operation. A piston rod 130 is connected at 65 one end to the piston 127. The other end of the rod 130 is provided with a head 131 which slides within an aperture within the sleeve 121. When the piston 127 moves toward the right (Fig. 3), the engagement of the head 131 with the end surface of a sleeve 132 which is fixed 70 relative to the sleeve 121 causes the sleeve 121 and the footstock center 120 to move toward the right out of engagement with the work piece 87.

A collar 133 is pinned to the piston rod 130. A 75 compression spring 134 surrounds the piston rod

130 and is interposed between the collar 133 and the bottom of the hole in the sleeve 132 which is fixed relative to the sleeve 121. When fluid under pressure is admitted to the cylinder chamber 129 to move the piston 127 toward the left (Fig. 3), the collar 133 exerts a pressure on the spring 134 to compress the spring 134 and move the sleeves 121 and 132 so that the footstock center 120 moves into engagement with a center hole in the right-hand end of the piston 87 to be ground. The outer sleeve 122 may be adjusted longitudinally relative to the footstock 59 so as to adjust the compression of the spring 134 to hold the footstock center 120 in supporting engagement with the piston 87 with the desired pressure.

The footstock 59 also supports a truing apparatus by means of which the grinding wheel 15 may be readily trued. A diamond or other truing tool 140 is mounted in the right-hand end 20 of a truing tool supporting rod 141 which is slidably keyed within an aperture 142 formed within the footstock 59. An adjusting screw 143 is screw threaded into the truing tool holder 141 and is rotatably supported in an end cap 144 mounted 25 on the end of a projecting boss 145 of the footstock 59. A manually operable adjusting knob 146 mounted on the left-hand end of the adjusting screw 143 serves to facilitate transverse adjustment of the truing tool 140 to compensate 30 for wheel wear and also to advance the truing tool the desired amount when initially setting up the machine for a predetermined grinding operation. The diamond or truing tool 140, except for a compensating adjustment, is normally held 35 in a fixed position with respect to the footstock 59 and rock bar 52.

The rock bar 52 is provided with a work loading fixture 150 having a V-shaped work supporting surface 151 upon which a piston 87 to be ground may be placed. The work supporting surface 151 is arranged to support the right-hand end of the piston 87 (Fig. 3) until the footstock center 120 is moved into operative supporting engagement with the work piece. Movement 45 of the center 120 into an operating position raises the piston 87 so that the piston 87 does not contact the surface 151 during the grinding operation.

It is desirable that the truing tool 140 normally 50 be held in a fixed position with respect to the rock bar 59 and that the bar be rocked to an inoperative position for a truing operation. In the preferred construction, a mechanism is provided which is actuated by and in timed relation with the traversing movement of the table 11 for automatically rocking the bar 52 to and from an inoperative position, that is, with the work piece 87 separated from the periphery of the grinding wheel 15, and the master cam 90 separated from the follower roller 95 before and after a truing operation. A lever 160 is mounted on the right-hand end of a rock shaft 161 (Fig. 5) which is journalled in a bracket 162 carried by the swivel table 44. The right-hand end of the 60 lever 160 (Fig. 6) is provided with a yoke-shaped projection 163 which straddles a stud 164. The stud 164 is fixedly mounted relative to an arm 165 which is formed integral with the rock bar 52. A compression spring 166 surrounds the 65 stud 164 and is interposed between the arm 165 and a collar 167. The yoke 163 of the arm 160 engages the collar 167 and when the lever 160 is rocked in a clockwise direction (Fig. 6), the spring 166 is compressed and the arm 165 rocked 70

75

to rock the rock bar 52 to an inoperative position. The movement of the rock bar to an inoperative position is limited by means of an adjustable stop screw 168 which is carried by the arm 165.

The shaft 161 supports at its left-hand end (Fig. 5) a downwardly projecting lever 170. A stud 171 pivotally connects the lever 170 with a toggle lever 172. A toggle lever 173 is pivotally supported by a stud 174 fixed to the swivel table 44. A stud 175 connects the toggle lever 172 and 173. The toggle lever 172 is preferably formed in the shape of a bell crank lever having a downwardly projecting arm 176 which supports a rotatable roller 177 at its lower end on a stud 178. The roller 177 is arranged in the path of a cam 179 which is fixedly mounted on the front of the machine base 10. The straight portion of the cam 179 maintains the rock bar 59 in an inoperative position to hold the truing tool in a fixed truing position as it is traversed across the periphery of the grinding wheel 15 to true the same.

In the full line position (Fig. 6), the toggle levers 172 and 173 are in a substantially straight-line position and the lever 170, shaft 161 and lever 160 are rocked in a clockwise direction to compress the spring 166 and to shift the arm 165 and the rock bar 52 to an inoperative position for a truing operation with the stop screw 168 in engagement with the swivel table 44. When the table 11 is traversed toward the right, that is toward a grinding position, the piston 87 moves into position 87a in operative relation with the grinding wheel 15, and the roller 177 rides along and down the surface of the cam 179 and assumes the position 177a. As soon as the roller 177 rides down the incline of the cam 179, the released compression of the spring 166 (Fig. 6) as well as the released compression of the spring 168 (Fig. 2) serves to rock the rock bar 52 into an operative position with the master cam 80 in operative engagement with the master cam roller 95. During this movement, the lever 160, the lever 170, and the toggle levers 172 and 173 and the arm 176 move into the broken line positions 160a, 170a, 172a, 173a and 176a. A stop screw 180 carried by the swivel table 44 serves to limit the rocking movement of the lever 170 and 160 in a counterclockwise direction (Fig. 6). When the table 11 is moved toward the left, the roller 177 and the levers connected therewith operate automatically to rock the rock bar 52 into an inoperative position as the ground piston is moved into its truing position.

To facilitate locating the table 11 with the work piece 87 in a predetermined position with relation to the grinding wheel 15, a stop device is provided. A bracket 125 is fixedly mounted on the base 10. The upper end of the bracket 125 carries an adjustable stop screw 126 which is arranged in the path of a stop lug 127 which is adjustably supported on the front edge of the table 11 by bolts which pass within a T-slot 65 formed therein.

Fluid under pressure for operating the footstock 59 may be supplied by any suitable means either from a central fluid pressure system within the plant or a fluid pressure pump contained within the base 10 of the machine. Fluid under pressure passing through a pipe 191 from the source of supply enters the valve 190 and in the position illustrated in Fig. 1 passes through the pipe 192 into the cylinder chamber 129 to move the footstock center 120 into operative support.

ing engagement with the work piece 87. During this movement of the footstock center 120, fluid within the cylinder chamber 128 is exhausted through a pipe 193, through the valve 190, and out through a pipe 194. A throttle valve 195, preferably of a needle valve type, is placed in the pipe line 194 and serves to regulate the speed of movement of the footstock center 120 into operative engagement with the work piece 87.

If it is desired to grind a cylindrical surface, the rock bar 52 may be locked in a fixed position with the master cam 98 out of engagement with the master cam roller 95. A nut 108 is screw threaded on the upper portion of the stud 101 above the arm 106 which projects from the rock bar 52. The nut 108 normally is maintained out of engagement with the arm 106. By tightening the nut 108, that is, adjusting it downward until the nut engages the arm 106 and moves it downwardly until the stop screw 168 limits the movement of the rock bar 52, the rock bar may be held in a fixed position for a cylindrical grinding operation.

The operation of this machine will be readily apparent from the foregoing disclosure. Assuming all of the mechanisms to have been previously adjusted, a piston 87 to be ground having a pin 116 passing through its wristpin bore is placed in position with its open end engaging the frusto-conical surface 116 and the yoke-shaped driver 115 engaging the pin 116. The outer end of the piston 87 rests upon the surface 151 of the work loading bracket 150. A control valve 190 is then actuated to admit fluid under pressure to the cylinder chamber 129, which serves to move the footstock center 128 into operative supporting engagement with the work piece 87, thus raising the footstock end of the work piece from the work loading fixture 150. The manually operable hand wheel 21 is then rotated to traverse the table 11 toward the right until the stop lug 187 engages the stop screw 186 to locate the piston 87 in a predetermined grinding position with relation to the grinding wheel 15. 25 30 35 40

During the longitudinal shifting and positioning movement of the table 11, the roller 177 rides along and down the cam face 179, thereby releasing the compression of the springs 166 and 100, which serves to rock the bar 52 into an operative position with the master cam 98 engaging the periphery of the master cam roller 95. The headstock motor 76 and grinding wheel motor 29 having been previously set in motion by means of push button switches located on the front of the machine base, the grinding operation proceeds and the feed wheel 49 is manually rotated to feed the grinding wheel 15 toward and into the work piece 87 to grind it to the predetermined size. During this feeding movement of the grinding wheel 15, the rotation of the headstock spindle 60 and work piece 87 serves, through the master cam 98 and the follower roller 95, to oscillate the work piece 87 toward and from the periphery of the grinding wheel 15 so as to generate or grind a predetermined oval or elliptical contour on the periphery of the piston being ground. By providing a master cam 98 of the desired shape, any desired shape may be produced on the periphery of the piston or object being ground.

After the feeding has continued until the work has been reduced or ground to the required size, the feed wheel 40 is then rotated in a clockwise direction (Fig. 1) to move the wheel 15 out of grinding contact with the work 87. The finish ground piston 81 may then be removed from the 75

machine and replaced with an unground piston for the next grinding operation. If it is desired to true the grinding wheel, the manually operable traverse wheel 21 is then rotated to shift the 5 table 11 longitudinally toward the left into a truing position, as indicated in Figs. 1 and 3. During this movement of the table 11 to a grinding wheel truing position, the engagement of the roller 177 with the cam 179 serves to rock the 10 levers 176, 173, 172, 170 and 169 into the position illustrated in Fig. 6 automatically to rock the rock bar 52 and truing tool 140 into an inoperative fixed truing position. Continued traversing movement of the table traverses the truing tool 15 140 across the operative face of the grinding wheel 15 to true the same.

It will thus be seen that there has been provided by this invention apparatus in which the various objects hereinabove set forth together 20 with many thoroughly practical advantages are successfully achieved. As many possible embodiments may be made of the above invention and as many changes might be made in the embodiment above set forth, it is to be understood that 25 all matter hereinbefore set forth or shown in the accompanying drawings is to be interpreted as illustrative and not in a limiting sense.

I claim:

1. In a piston grinding machine having a rotatable grinding wheel and a rotatable work support which are movable longitudinally and transversely relative to each other, means to traverse said work support and grinding wheel longitudinally relative to each other, means to feed said work support and grinding wheel transversely relative to each other, means to rotate said work piece, yieldable means to hold said work support in an operative position, an adjustable truing tool on said work support, means to traverse said table longitudinally to and from a truing position, and means actuated automatically when the table is traversed toward a truing position to move said work support transversely to locate the truing tool in a predetermined truing position.
2. In a piston grinding machine having a rotatable grinding wheel and a rotatable work support which are movable longitudinally and transversely relative to each other, means to traverse said work support and grinding wheel longitudinally relative to each other, means to feed said work support and grinding wheel transversely relative to each other, means to rotate said work piece, yieldable means to hold said work support in an operative position, an adjustable truing tool on said work support, means to traverse said table longitudinally to and from a truing position, and means actuated automatically when the table is traversed toward an operative position after a truing operation to move the work support transversely into an operative position.
3. A piston grinding machine having a longitudinally traversable table, a transversely movable wheel slide, a rotatable grinding wheel supported thereon, a transversely movable rotatable work support on said table, yieldable means to hold said work support in an operative position, an adjustable truing tool on said work support, means to traverse said table longitudinally to and from a truing position, and means actuated automatically when the table is traversed toward a truing position to move said work support transversely to locate the truing tool in a predetermined truing position.
4. In a piston grinding machine having a rotatable grinding wheel and a rotatable work sup-

port which are movable longitudinally and transversely relative to each other, means to traverse the work support and grinding wheel longitudinally relative to each other, means to feed said work support and grinding wheel transversely 5 relative to each other, means to rotate said work support, means to clamp a work piece thereon, a pivotal support for said work support, means including a master cam and a follower to rock said work support to cause the work to approach 10 and recede from the grinding wheel to grind a non-circular shape on the periphery of the work piece, a truing tool adjustably supported on said pivotally mounted work support, and means actuated by the relative longitudinal movement between the grinding wheel and work support to rock said work support to an inoperative or truing position for a grinding wheel truing operation.

5. In a piston grinding machine having a longitudinally traversable table, a transversely movable slide, a rotatable grinding wheel supported thereon, a rotatable work support on said table including a rock bar, a head and footstock formed integral therewith rotatably to support a piston 20 to be ground, a rotatable master cam and a follower to rock said bar during rotation of said headstock to generate a predetermined contour on the piston being ground, a truing tool adjustably supported on said rock bar, means to adjust 30 the truing tool relative to the rock bar, and means including a cam and a follower actuated during the traversing movement of the table toward a truing position automatically to rock said bar to an inoperative position and to hold the truing 35 tool in a fixed truing position during a wheel truing operation.

6. A piston grinding machine having a longitudinally movable table, a transversely movable wheel slide, a rotatable grinding wheel thereon, a work support on said slide including a pivotally mounted rock bar, a head and footstock thereon rotatably to support a piston to be ground, a rotatable master cam and a follower to rock said 40 bar to generate a predetermined contour on the piston being ground, a truing tool adjustably supported on said rock bar, and means including a cam and a follower which serve during a traversing movement of the table toward a truing position to rock said bar to a fixed inoperative truing 45 position during a truing operation and automatically to shift said bar to an operative position with the master cam in engagement with the follower when the table is traversed from a truing to an operating position.

7. In a grinding machine having a longitudinally traversable table, a transversely movable slide, a rotatable grinding wheel supported thereon, a rotatable work support on said table including a rock bar, a head and footstock on said rock 60 bar, a headstock spindle rotatably journaled in said headstock, a master cam follower roller, a master cam removably mounted on the end of the headstock spindle adjacent to the grinding wheel, and a work supporting and driving member adjustably mounted on said master cam.

8. In a grinding machine as claimed in claim 1, the combination with the parts and features therein specified, of a stop to locate said bar in an inoperative or truing position, yieldable means 70 normally to maintain said bar in an operative position with the master cam in operative engagement with the follower, means including a toggle lever mechanism on said table to rock said bar to an inoperative position, and means includ-

ing a cam on said base to actuate said toggle lever mechanism when the table is traversed longitudinally toward a truing position to rock said bar to an inoperative position and to hold it in 5 an inoperative or truing position during a grinding wheel truing operation.

9. In a grinding machine as claimed in claim 1, the combination with the parts and features therein specified, of a stop to locate said bar in 10 an inoperative or truing position, yieldable means

normally to maintain said bar in an operative position, means including a toggle lever mechanism to rock said bar to an inoperative position, and means including a cam which is arranged to actuate said toggle lever mechanism when the 5 table is traversed longitudinally toward a truing position to rock said bar into an inoperative position and to hold it in said position during a grinding wheel truing operation.
